PRODUCTION OF PRODUCER GAS

James Alexander Macdonald, Nakuru, East Africa

Original application June 30, 1930, Serial No. 465,018, and in Great Britain July 29, 1929. Divided and this application August 11, 1932. Serial No. 628,427

4 Claims. (Cl. 48—203)

This invention relates to the production of combustible gases (which will hereinafter be referred to as producer gas) by reacting on fuels with air and water vapour under heat, and has 5 for its object to provide an improved method therefor.

In use, the producer gas may be cooled and dehydrated, as well as cleaned, by any of the usual suitable means, but it is a further object of the 10 invention to provide an apparatus which will deliver a producer gas of good quality together with water in a state adapted to be fed directly to an engine without previous dehydration.

The invention rests principally upon the three 15 following considerations:—

(1) It is possible to maintain an incandescent zone within a producer so hot that water finds great difficulty in extinguishing it provided that the reaction is directly supplied with air or oxygen under a forced draught, as, for example, by admitting the air through a pipe of restricted diameter that causes it to move with considerable velocity.

(2) Such a reaction zone tends to become very 25 hot and to spread; but it can be kept cool and confined to a limited volume by surrounding it with a comparatively cool atmosphere of a non-combustible e. g. steam.

(3) It is an advantage to supply H_2O to the 30 reaction in the form of fluid and not of gas, i. e. water not steam, if this can be done satisfactorily without extinguishing the fire; because the specific gravity of water is over 1,000 times greater than that of steam and a sufficient quantity of H_2O can be injected without interfering with the adequacy or accessibility of the oxygen for combustion. Moreover the cooling effect of a given weight of fluid so vastly exceeds that of an equivalent of steam that the tendency to 35 spread is correspondingly more easily checked.

The preferred form of apparatus for carrying out the invention primarily comprises a producer gas plant having a combustion chamber of substantial volume, a bottom adapted to hold water 45 up to a certain level, an air inlet pipe of restricted diameter extending within said chamber and adapted to create an incandescent zone of limited volume and high temperature at or adjacent the delivery end thereof, and means to 50 deliver a supply of water on to said incandescent zone.

The apparatus forms the subject of a co-pending patent application No. 465,018.

As will hereinafter appear, a substantial volume 55 of water vapour is created and maintained with-

in the body of the chamber, the localized incandescent zone being surrounded by an atmosphere of said vapour and the primary products of the reaction being immediately cooled by it and "fixed" and delivered in their original state 60 without the occurrence of serious secondary reactions. Further, the walls of the chamber are maintained much cooler than is usual in such plants even after prolonged use.

The producer gas may be delivered with an 65 amount of water vapour (whether in a free state or not) which considerably exceeds normal practice, and at a temperature below 100° C. If dried, it discloses on analysis a producer gas of good quality; but it is also readily capable of direct 70 use without drying.

The invention is applicable for use with solid fuel such as coal or charcoal, or with liquid fuels. In the former case, the height of the inlet pipe above the bottom must be sufficient to provide 75 for the accumulation of a certain amount of ash.

The outlet pipe is preferably situated opposite and slightly above the inlet pipe, and its penetration within the chamber is preferably adjustable to provide means for controlling the re- 80 action.

The apparatus as described may be coupled directly to an internal combustion engine with the interposition of nothing more than any simple device for extracting particles of solid carbon, 85 and when a steady working condition has been reached, the nature of the products is determined by the amount of water supplied by means of the inlet pipe and the degree of penetration of the outlet pipe within the chamber. 90

The invention is illustrated in the accompanying drawing in which

Figures 1 and 2 show in vertical and horizontal cross section diagrammatic representations of a plant arranged for use in accordance with the 95 invention and intended for use with charcoal.

In the form illustrated, the plant comprises a cylindrical preferably metallic chamber 1 having an upper closure 2 for the insertion of fuel. The inlet pipe 3 penetrates adjustably within 100 the chamber as shown, and a spray 4 is arranged to direct a finely-divided jet of water through the inlet pipe on to the incandescent zone as high up as possible. Where the draught is sufficiently forced, a drip of water will be suitably broken up 105 and whirled in by the rush of air.

The outlet pipe 5 is adjustably mounted in the opposite wall of the chamber coaxially with the pipe 3. Its penetration within the chamber may be extended to the points indicated in dotted 110

lines. It is arranged slightly higher than the inlet to avoid its being flooded.

The inlet pipe 3 is arranged as low as convenient for the accumulation of ash, and to provide an overflow for any water collecting in the bottom of the chamber, without being sufficiently high to have much waste fuel below the fire.

In operating such a plant, the fire is first lit, e. g. by applying a lighted torch to the pipe 3, and when combustion is satisfactorily established, water, at first in small quantities, is injected through the spray 4. Circulation is effected by applying pressure to the pipe 3 or, preferably suction to the pipe 5.

From an examination of the temperature of the walls of the container during warming up and running, it would appear that when a steady condition has been reached the flame is confined to an inner space which may correspond probably to that indicated at 6, the hottest part of the flame where combustion of the fuel principally takes place being indicated at 7, and 8 indicating the inner zone where no combustion takes place.

The actual incandescent zone probably varies in volume slightly from time to time in accordance with engine demand and/or rate of air supply. The reaction zone may be regarded as being bounded by a pulsating flexible envelope e. g. that within the isotherm 10. When the water vapour reaches the isotherm 9, the reaction extracts from it part which is sufficient for its own continued propagation. In general, the water on entering is instantly converted into jets of vapour which expand outwardly in all directions away from the reaction zone with semi-explosive force. These vapour jets enter into the outer reaction zone and also help to form the roughly concentric enveloping zone about the reaction zones and maintain the surrounding atmosphere of water vapour against condensation losses &c. Another part of the water falls into the pan-like bottom where a certain amount is constantly evaporated and helps to envelop the underside of the incandescent zone. Further, the zones of equal temperature under steady conditions appear to correspond generally with the isothermals shown at 9, 10, 11, 12. It is believed that the isothermal 7 represents roughly the

zone of reaction between the oxygen of the air and the carbon of the charcoal to produce carbon dioxide: that the isothermal 6 represents the zone of reduction to carbon monoxide: the isothermal 9 that where steam enters into reaction with the carbon to produce carbon monoxide and hydrogen. The two latter reactions absorb heat and the whole of the reaction zones are surrounded by a roughly concentric envelope of vapour roughly represented by the isothermal 10. A body of current of water vapour is thus positioned between the edge of the flame 6, and the right-hand wall of the chamber in Figure 1, so that even at the lowest part of the chamber the temperature of the wall does not exceed a value which can be withstood by metal, and it is not necessary to use fire-brick or any special lagging.

The temperature at the central part of the top underneath the closure 2 remains hotter than the temperature in other parts of the roof which is all more or less a cloud zone with descending rain, and the temperature of the left-hand wall in Figure 1 is hottest about one-third or one-quarter way down, the temperature immediately above the outlet pipe 5 remaining substantially cool. It will be appreciated that with a given de-

mand on a chamber of fixed size, the contributory factors which together determine the exact size and position of the flame are the size of fuel, the diameter and intrusion of both inlet and outlet pipes, and the amount of water supplied.

Under suction the air is supplied to inlet pipe 3 at atmospheric pressure, the end of the pipe being merely left open. The diameter of pipe 3 is sufficiently restricted to ensure that the air moves therethrough with substantial velocity under the suction applied to pipe 5 so as to apply air under forced draught to the incandescent zone. The supply of water, however, is controlled so that excess is always present above the amount normally necessary to the making of good gas. The bottom of the container may be kept wet or even flooded, without the gas becoming debased as would be expected.

With air supplied at substantial velocity and the water projected horizontally as described, it is impossible for the incandescent zone to be extinguished, as the liquid water is so quickly transformed chemically or into steam, or removed from the incandescent zone. Excess of water does not cause any substantial penetration of water or steam into the reaction zone itself (beyond the amount which the reaction requires) since the pressure is much higher at the inner part of the reaction zone, which is the hottest part, than at the boundary. Such excess of water, therefore, only results in slightly restricting the volume of the reaction zone (isothermal 6) and in adding to the quantity of water in the pan-like bottom.

The steam formed is continually being condensed in the upper part of the producer, falling downwardly through the mass and being either re-converted to steam or reaching the pan-like bottom; but this transformation is insufficient in quantity to quench the flame in the reaction zone.

The amount of water supplied after the bottom has been flooded may be as much as 1 kg. or 1½ kg. per 1 kg. of charcoal. An actual plant which has given satisfactory results comprises a drum 90 c.m. high and 52 c.m. diameter with inlet and outlet pipes 2.5 to 5 c.m. This plant will drive a four cylinder automobile engine rated at 10-20 H. P. at 1100 revolutions per minute, the engine being altered only to provide a compression ratio of about 6 to 1.

In a modification, the plant comprises a cylindrical chamber 180 c.m. high and 67 c.m. diameter, the inlet and outlet pipes being 5 c.m. or 7 c.m. diameter. When this plant was coupled to a four-cylinder 75 H. P. engine at 550 revolutions, the consumption was in the region of 32 kg. of water per hour. The amount of water supplied when coupled direct to a single cylinder engine designed to give 8 H. P. at 350 revolutions per minute was about 5 kg. per hour, the only adjustment required other than the setting of the spray valve being a variation of the penetration of the outlet pipe 5 which advantageously should be given a different setting for engines differing in output by 10 H. P. or more. With this plant the inlet pipe is about 7 c.m. above the bottom of the chamber.

By controlling the water supply and the penetration of the outlet pipe 5 within the chamber, a very delicate control of the operation of the plant is provided: when the plant is, for example, coupled to an internal combustion engine, comparatively slight axial displacement of the outlet pipe 5 produces appreciable variation in the power output probably owing to the fact that the gases are drawn off from a more suitable zone

of the total reaction so that an optimum position is readily found for the outlet pipe. After this position is reached, the engine may be controlled in the ordinary way by throttle.

5 If a plant designed for an engine of given horse-power is utilized with an engine of larger horse-power, the suction in pipe 5 will be increased, and the plant generally will work at higher temperatures. Within reasonable limits, it will, however, respond to the increased power output on increase of the amount of water supply through the nozzle 4, and resetting of the outlet pipe 5, and of course more frequent feeding of fuel through the closure 2.

15 The invention is not confined to the use of solid fuel, as it may be employed with liquid fuels which may be burnt in a similar kind of closed chamber, the liquid fuel being separately injected or applied through the air inlet.

20 The plant as described above can be operated successfully with oil fuel either by direct injection or by mounting a drip feed device in the upper wall of the inlet pipe 3. The combustion zone in such case is localized by providing a mass 25 of solid material such as fire brick chippings adjacent the end of the inlet pipe.

The said plants can also be operated successfully with soft coal or anthracite in the form of nuts, although in such case a tar-extractor may 30 be required.

In all cases it is important to have a chamber of sufficient volume that the incandescent zone is localized and is entirely enveloped in an atmosphere of water vapour, and that an extended 35 path is provided for the circulation of the vapour and products of combustion which probably move in zones corresponding in direction to the general direction of the isothermals indicated, the water vapour serving not only to lower generally the 40 temperature of the outlet gases but also preventing the production of secondary reactions in zones substantially remote from that of the flame 6.

It is very important that all joints of the fuel 45 and ash closures be tightly sealed, and all air leaks into the chamber be avoided, the chamber being completely closed except for the inlet and outlet pipes 3, 5.

With the arrangement described, the incandescent zone remains limited in volume and does 50 not tend to creep up the chamber on prolonged use, probably owing to upper condensation and

the movement of the water vapour from the upper part of the chamber towards the outlet pipe.

Although the localized incandescent zone may be at 1300° C. or more, it is an advantage of the invention that the temperature round the walls of the container is maintained low so that a metal container of ordinary quality may be employed. The water may be fed through a nozzle arranged above the inlet pipe, so as to deliver the jet on the top of the incandescent zone.

I claim:—

1. A method of generating producer gas consisting in supplying air to a closed firing chamber by means of a restricted inlet to create a highly incandescent zone adjacent to the delivery end of the said inlet, and in delivering on to the said zone water in excess of the reaction requirements to localize the said zone and maintain the base of the chamber wet.

2. A method of generating producer gas consisting in supplying air to a closed chamber by means of a restricted inlet near the bottom thereof to create a very hot zone near the end of the said inlet surrounded by cooler reaction zone, and in projecting water on to the said hot zone in sufficient volume to restrict the said zone by conversion of water into vapor forming an enclosing roughly concentric envelope about the said zone 105 and the cooler reaction zone, and to enter into the reaction in the outer part of the said cooler reaction zone while maintaining the base of the chamber wet.

3. A method of controlling the generation of 110 producer gas in a closed chamber provided with inwardly projecting inlet and outlet by forming reaction zones surrounded by a roughly concentric vapor envelope produced by projecting water toward the hottest zone sufficient in quantity to 115 leave liquid water outside the reaction zones in excess of the reaction requirements.

4. A method of controlling the generation of 120 producer gas in a closed chamber provided with inwardly projecting air inlet and gas outlet by forming reaction zones surrounded by a roughly concentric vapor envelope produced by projecting water toward the hottest zone sufficient to 125 leave liquid water outside the reaction zones in excess of the reaction requirements, the inward penetration of the air inlet and the quantity of water supplied being variable.

JAS. ALEX. MACDONALD.
